(57) **CLAIM**

The ornamental design for a body of a wire harness protector, as shown and described.

DESCRIPTION

FIG. 1 is a front, top, and right side perspective view of a body of a wire harness protector showing my new design; FIG. 2 is a front view thereof;

FIG. 3 is a rear view thereof;

FIG. 4 is a top plan view thereof;

FIG. 5 is a bottom plan view thereof;

FIG. 6 is a right side view thereof; a left side view being an identical image of FIG. 6;

FIG. 7 is an enlarged view of the portion indicated by line 7-7 in FIG. 1;

FIG. 8 is an enlarged view of the portion indicated by line 8-8 in FIG. 4;

FIG. 9 is a cross sectional view taken along line 9-9 in FIG. 8; and,

FIG. 10 is a cross sectional view taken along line 10-10 in FIG. 8.

The features shown in broken lines in the drawings depict environmental subject matter only and form no part of the claimed design.
